UNITED STATES PATENT OFFICE

ERNST HURLBRINK, OF BERLIN, AND GEORG MEISTER, OF BERLIN-BLANKENBURG, GERMANY, ASSIGNORS TO FABRIK EXPLOSIONSSICHERER GEFASSE SALZKOTTEN G. M. B. H., OF SALZKOTTEN, GERMANY, A CORPORATION OF GERMANY

DISPENSING APPARATUS

Application filed June 22, 1928, Serial No. 287,579, and in Germany July 1, 1927.

Our invention relates to improvements in dispensing apparatus, and more particularly in dispensing apparatus comprising a measuring receptacle, means for supplying the liquid thereto, and a pipe for removing the air or gas from the liquid supplied to the said receptacle. In apparatus of this type throttling means have been provided for arresting the supply of liquid after filling the receptacle and for indicating to the attendant that the receptacle has been properly filled. In constructions now in use the area of the vent through which the air is removed from the receptacle must be comparatively small, in order to avoid the loss caused by the continued supply of liquid after filling of the receptacle has taken place. However, if the said area is small the resistance opposed to the air escaping through the vent when filling the receptacle is high, so that filling is made difficult and takes much time. Further, when delivering the liquid from the measuring receptacle the air flows through the vent into the receptacle only slowly, so that a vacuum is produced within the receptacle which interferes with a rapid discharge of the measured liquid.

One of the objects of this improvements is to provide an apparatus in which the resistance opposed to the air when filling the receptacle or delivering the liquid therefrom is reduced, so that the filling and the discharging of the liquid is accelerated, and in which notwithstanding the rapid flow of the liquid the supply of an excess of liquid is prevented, and with this object in view our invention consists in providing a comparatively large discharge opening for the air, and providing the same with means for reducing the cross-sectional area of the said discharge when the receptacle has been nearly filled. For this purpose a valve is provided in connection with the said vent which is adapted partly to close the vent, and which is moved into closing position by the liquid being supplied to the receptacle. When the apparatus is thus constructed the air can readily escape through the vent during the filling of the receptacle, so that filling is not retarded by slow and obstructed escape of the air from

the top part of the measuring receptacle; after the receptacle has been filled or partly filled, the valve is automatically thrown into operation for reducing the area of the vent, so that only a small amount of the liquid can escape through the same. Further, the pressure within the receptacle is increased, so that the power needed for operating the filling apparatus is increased and the attention of the attendant is accordingly called to the fact that the receptacle has been filled. When discharging the liquid from the receptacle, the valve is automatically unseated, so that the air has an unimpeded access to the receptacle, and a rapid discharge of the liquid is insured.

Other objects of the invention will appear from the following description.

For the purpose of explaining the invention several examples embodying the same have been shown in the accompanying drawings, in which the same reference characters have been used in all the views to indicate corresponding parts. In said drawings,

Fig. 1, is a diagrammatical sectional elevation showing the filling mechanism, the measuring receptacle, and the pipe through which the air is discharged from the measuring receptacle,

Fig. 2, is a sectional elevation on an enlarged scale showing the top part of the measuring receptacle, the pipe for withdrawing the air and the valve for partly closing the said pipe,

Fig. 3, is a similar sectional elevation showing a modification,

Fig. 4, is a diagrammatical sectional elevation similar to the one illustrated in Fig. 1 and showing a modification, and

Figs. 5 and 6, are sectional elevations on an enlarged scale and similar to those shown in Figs. 2 and 3, and showing modifications of the apparatus controlling the escape of the air.

In the example shown in Fig. 1 the dispensing apparatus comprises a cylindrical measuring receptacle 2 having a concentric top part 1 reduced in diameter, a hand operated pump 3 for supplying the liquid to the filling receptacle 2, pipes 4, 4^a connecting the

pump 3 with the bottom part of the receptacle 2, a discharge pipe 6 for delivering the liquid from the receptacle 2, a two-way cock 5 adapted to connect the pipes 4, 4^a or the pipes 4^a and 6, and a pipe 7 disposed concentrically within the receptacle 2 and ending within the portion 1 thereof. The apparatus shown in Fig. 1 is used for example for supplying liquid fuel. The pipe 7 is connected with the tank from which the liquid is taken, and any excess of liquid supplied to the receptacle 2 escapes through the pipe 7.

In the construction shown in Fig. 2 the pipe 7 is provided at a point slightly below its top face 8 with an annular valve seat 9, and on the said seat there is located an annular separating disk 10 having a comparatively large concentric opening 11 and a small passage 12. The opening 11 is adapted to be closed by a valve 13 the stem of which is guided in a frame 14 depending from the disk 10, said valve 13 being normally held away from its seat by a spring 15.

The operation of the apparatus is as follows: When supplying the liquid through the pipes 4, 4^a to the receptacle 2 the air can rapidly escape from the receptacle through the large opening 11 and the small passage 12 of the disk 10, so that the resistance opposed to the incoming of the liquid is small, and the receptacle 2 is readily filled. When the level of the liquid rises above the top face 8 of the pipe 7 the liquid acts on the valve 13 and presses the same on the disk 10 against the pressure of the spring 15, so that the opening 11 is closed. At this stage the inner part of the receptacle communicates with the pipe 7 only through the small passage 12, so that only a small amount of liquid together with the air or gas which may have collected above the top 8 of the pipe 7 escapes from the receptacle 2.

When setting the cock 5 into discharging position, the liquid flows from the receptacle 2 and through the pipes 4^a and 6. As this occurs the valve 13 is immediately raised from its seat by the action of the spring 15 and a vacuum temporarily created by the liquid being discharged from the receptacle 2. Further, the separating disk 10 is raised from the annular seat 9 by the air rushing upwardly through the pipe 7, so that the vacuum within the receptacle 2 is quickly destroyed, and the liquid is rapidly discharged.

In the construction shown in Fig. 2 the disk 10 also constitutes a check valve and permits the air to flow back into the receptacle 2. Therefore the discharge of the liquid from the receptacle is not retarded even though the area of the opening 11 and the passage 12 is no larger than is necessary for the expulsion of the air when filling the receptacle. Preferably the area of the said opening and passages 11, 12 is of the smallest dimensions needed for this purpose, because otherwise the

valve 13 would not be closed rapidly enough after the filling of the receptacle has been completed.

In the modification shown in Fig. 3 the top end 8 of the pipe 7 is closed by a hood 16 of mushroom shape and having a tubular nipple 18 screwing into a bushing 19 fitted to the upper end of the pipe 7. The said hood 16 is provided in its bottom with a series of concentrically arranged passages 17 connecting the receptacle 1 with the interior of the hood 16 and the pipe 7. The top of the bushing 19 provides a support for an annular valve disk 20 which is guided on the nipple 18, and includes a single passage 21 located in registry with one of the passages 17. The disk 20 is made from light material, so that it may easily be lifted by the liquid rising within the receptacle 1 into position for closing all the passages 17 except the one located in registry with the passage 21.

The operation of the apparatus is as follows: The liquid rising within the receptacle 2 drives the air through the passage 17 and into the pipe 7. When the receptacle has been filled the valve disk 20 is lifted by the liquid into position to close all of the passages 17 except one, so that a material loss of liquid is prevented, and the pressure within the receptacle 2 is increased thus indicating to the attendant that the receptacle has been filled. Any excess of liquid supplied to the receptacle overflows through the passages 21, 17 and the pipe 7 to the tank.

When delivering the liquid from the receptacle 2, the valve disk 20 immediately drops to the top face of the bushing 19, so that all the passages 17 are laid open, and the air has free access from the pipe 7 into the measuring receptacle 2. Thus a vacuum which would interfere with the rapid dispensing operation cannot be produced. Also in this construction the measuring receptacle is rapidly filled and emptied, and yet there are throttling means operative at the end of the filling operation and having the results stated above.

In Figs. 4 to 6 we have shown modifications in which the upper part of the pipe 23 through which the air is removed from the receptacle 1, 2 is covered by a hood 22 which is closed at its top and open at its bottom 33, an annular passage 27 being provided between the said hood and the upper part of the pipe 23. Near its top the hood is formed with a transverse partition comprising a downwardly directed nipple 24 screwing into a bushing 25 which is fitted into the upper end of the pipe 23, said partition carrying the nipple 24 being provided with a concentrically arranged series of passages 26 establishing communication between the annular passage 27, the nipple 24 and the pipe 23. On the upper end 29 of the bushing 25 an annular valve disk 28 is supported, which is guided

on the nipple 24 and is provided with a single passage 30 corresponding in position to one of the passages 26. When raised away from the bushing 25 the disk 28 closes all the passages 26 except the one corresponding in position to the passage 30. In practice the passage 30 is very narrow, so that it permits only the passage of a very small amount of air, the flow of the air being so slow that any escape 10 of liquid from the receptacle 1 into the pipe 23 is prevented. As a matter of fact the passage 30 merely functions to permit a restricted escape of air.

In the construction shown in Fig. 5 a vent 15 31 is provided at the upper part of the hood 22 and above the passages 26, the said vent connecting the receptacle 1, 2 with the interior of the hood and the pipe 23. At the level of the passage 31 a mark 32 is applied to 20 the outer face of the upper position 1 of the receptacle 2, the said mark indicating level of the contents of the receptacle when the latter is filled to the desired extent.

In the modification shown in Fig. 6 the vent 25 31^a connecting the receptacle 2 with the pipe 23 is located below the partition containing the passages 26 and communicates with the annular passage 27 of the hood 22.

The operation of the apparatus shown in 30 Figs. 4 and 5 is as follows: When forcing the liquid by means of the pump 3 into the receptacle 2 the air escapes through the annular passage 27, the passages 26 and the pipe 23. When the liquid has risen to the bottom 35 33 of the hood 22, it rapidly rises within the annular passage 27, and finally it lifts the valve ring 28 so as to close the passages 26 except the one which registers with the passage 30. At this stage the supply of liquid is ac- 40 cordingly almost entirely interrupted.

The air confined outside the hood 22 within the top 1 of the receptacle can escape only at a slow rate through the passage 31, so that if the operation of the pump 3 is continued, 45 the level of the liquid rises within the top part 1 and the air above the same slowly escapes through the passage 31. The higher the pressure of the pump, the sooner the top 1 is filled with liquid.

50 While the supply of liquid is thus retarded until the receptacle is filled to the mark 32, any gas or air contained within the liquid is separated therefrom, and escapes through the passage 30 and the passage 26 which registers therewith. When the liquid has risen to the mark 32, the whole receptacle is filled with liquid which is free of air or gas bubbles.

By reason of its concentric arrangement 60 the part 1 of the receptacle can be made of relatively small diameter. Therefore errors in measurement caused by the difference of the levels between the measuring plane and the throttling element is reduced to a minimum.

In the modification shown in Fig. 6 the air confined within the hood before the end of the filling operation cannot escape directly to the pipe 23 but must first flow through the passage 31^a into the annular passage 27, 70 from which it flows into the pipe 23. Since there is the same pressure in the annular passage 27 and within the hood 1, independently of the pressure of the pump supplying liquid to the receptacle 2, the liquid rises 75 within the hood to the indicating mark 32 exclusively by the action of the difference of pressure caused by the difference of level between the surface of the liquid within the hood 1 and the surface of the liquid within 80 the passage 27 rising to the throttling part 26. Therefore, even if strong pressure is exerted by the pump for completing the filling, the level of the liquid rising within the hood 1 will only slowly come to the 85 measuring level 32. As a result of this, bubbles will be completely separated, and the rising of the liquid can be safely observed.

The liquid supplied to the receptacle 2 after closing the passage 26 within the hood 22 for completing the filling of the receptacle is taken exclusively from the downwardly directed branch of the pipe 4 which is likewise free from gas bubbles by reason of the slow movement of the liquid therethrough, 90 the gas being collected at the top of the said pipe. Since the capacity of the downwardly directed branch of the pipe 4 is at least equal to the amount of liquid needed for completing the filling, no new air or gas bubbles enter the receptacle 2 when filling 95 the hood 1 and the part of the receptacle 2 relieved from the gas.

When discharging the liquid from the receptacle 2 through the pipe 6 the valve ring 28 drops on the top part 29 of the bushing 25, so that the air has free access to the upper part of the receptacle 2 through the 100 whole series of passages 26.

Our improved system can be used in connection with dispensing systems comprising a single measuring receptacle, as well as in systems comprising a double measuring receptacle.

While in describing the invention reference has been made to particular examples embodying the same we wish it to be understood that our invention is not limited to the constructions shown in the drawings, and that various changes may be made in 110 the general arrangement of the apparatus and the construction of its parts without departing from the invention.

We claim:

1. An apparatus for dispensing liquids in 115 measured quantities, comprising a measuring receptacle having a supply and a discharge for the liquid, and means for discharging air or gas from said receptacle, said means comprising an opening of 120

125

130

determined area and means controlled by the liquid rising within the receptacle for reducing the area of the said opening.

2. An apparatus for dispensing liquids in measured quantities, comprising a measuring receptacle having a supply and a discharge for the liquid, and means for discharging air or gas from said receptacle, said means comprising an opening of predetermined area and a check valve constructed to partly close said opening and arranged to be set into opening position by a current of air flowing through said opening into the receptacle.
3. An apparatus for dispensing liquids in measured quantities, comprising a measuring receptacle having a supply and a discharge for the liquid, a pipe extending upwardly within said receptacle, a hood covering the upper portion of said pipe and communicating through a passage with the pipe, and means within said hood adapted to be acted upon by the liquid rising within the hood for reducing the area of said passage, said hood being formed with a vent through which the space located between the hood and the wall of the receptacle communicates with the pipe.
4. An apparatus for dispensing liquids in measured quantities, comprising a measuring receptacle having a supply and a discharge for the liquid, a pipe extending upwardly within said receptacle, a hood covering the upper portion of said pipe and communicating through a passage with the pipe, and means within said hood adapted to be acted upon by the liquid rising within the hood for reducing the area of said passage, said hood being formed near its top and below said vent with a passage through which the space located between the hood and the wall of the receptacle communicates with the pipe.

In testimony whereof, we have signed this specification.
